UNITED STATES PATENT OFFICE.

ALFRED M. ZIEGLER, OF ROXBURY, MASSACHUSETTS.

CAST-OFF FOR SUSPENDERS.

1,119,771.

Specification of Letters Patent.

Patented Dec. 1, 1914.

Application filed December 15, 1911. Serial No. 665,969.

To all whom it may concern:

Be it known that I, ALFRED M. ZIEGLER, a citizen of the United States, and resident of Roxbury, county of Suffolk, State of Massachusetts, have invented an Improvement in Cast-Offs for Suspenders, of which the following description, in connection with the accompanying drawing, is a specification, like characters on the drawing representing like parts.

This invention relates to suspenders, and more particularly to a suspender cast-off, which device, as is well known, is a form of detachable connection between the suspender-end or part which buttons onto or is otherwise attached to the garment, and the terminal portion of the main suspender-web or shoulder-strap, whereby the wearer can readily disconnect the suspender-web and the suspender-end when desired.

My present invention has for its object the production of an improved cast-off for suspenders of simple construction, attractive in appearance and efficient in use, and inexpensive to manufacture, the various parts being so constructed and arranged that assembling is facilitated, and the final completed product is of high quality and easy to operate.

The various novel features of my invention will be fully described in the subjoined specification and particularly pointed out in the following claims.

Figure 1 is a front elevation of a cast-off embodying my present invention, connecting the suspender-end and the terminal portion of the main suspender-web, the cast-off strip being shown in hook closing position; Fig. 2 is a similar view, but with the cast-off strip turned downward to uncover the hook and permit disengagement of the suspender-end therefrom; Fig. 3 is a left hand side elevation of the device shown in Fig. 2, with the suspender-end omitted; Fig. 4 is a rear elevation of the cast-off, the strip being open to uncover the hook; Fig. 5 is a left hand side elevation of the device in the condition illustrated in Fig. 1, the suspender-end being shown in section; Fig. 6 is a perspective view of the metallic connector forming a part of the cast-off, and through which all the pull or strain is transmitted from the suspender-end to the shoulder-strap or main web of the suspender.

In accordance with my invention the cast-

off comprises essentially a metallic connector bent in a peculiar form, a cast-off strip or web adapted to close the hook with which the connector is provided, and a loop attached to the connector and connected with the end or terminal portion of the suspender-web.

The connector is made of thin sheet metal and comprises a flat shank 1 shaped at its upper end to present a rearward and down-turned portion 2, preferably cut out at its downturned edge, as at 3, Fig. 4, for a purpose to be described, and which forms with the shank a cast-off receiving throat on the rear side of the shank. The lower end of the shank is bent to form an upturned longitudinally curved hook 4, said shank having an aperture 5, Fig. 6, near its upper end. As shown in Figs. 1, 2 and 5, the hook is adapted to detachably engage and sustain a suspender-end A, of any usual construction and adapted to be attached to the trousers or other garment to be supported.

The usual main shoulder-strap or web B of the suspender, partly shown in Figs. 1, 2 and 3, has attached to its lower or terminal end a loop 6, preferably made of stout wire, and having its bottom bar slightly dropped, as at 7, and of such length that the dropped portion will enter easily the throat formed by the bend 2 of the connector, the web B being reeved through the loop in well known manner.

8 designates a cast-off strip made of webbing or other suitable flexible fabric, said strip being applied to the back of the shank 1 and having its raw upper end 9 inserted into the throat formed by the downturned portion 2 and in substantial engagement with the drop 7 of the loop, as shown in Figs. 3, 4 and 5.

A tubular rivet 10 having its shank passed through the strip and through the hole 5 of the hook shank 1 serves to fixedly attach the cast-off strip to the shank, and said rivet also holds in place one member 11 of a two-part separable fastening of the well-known ball and socket type, said member 11 forming the ball or knob of such fastener. The head of such rivet, shown at the back of the cast-off strip, rests upon the latter close to the downturned end of the bend 2, and the cut-away part 3 of said bend enables the rivet to be properly positioned close to the bend.

As the upper end 9 of the strip 8 is in-

serted into the throat, the downturned portion 2 overlies said end and protects it, so that the raw transverse edge can be used, thereby obviating binding or otherwise finishing such end of the strip, and as the portion 2 and the rivet hold the said end of the strip securely in place it in turn closes the open end of the throat and maintains the loop 7 in place therein.

10 It will thus be seen that I make use of the end of the cast-off strip as the means for preventing the loop 7 from being disengaged from the throat, and I also employ the means for fastening the cast-off strip to 15 the shank as part of the means for separably securing the end of the cast-off in hook-closing position. By this construction I am enabled to reduce the number of parts and the cost of manufacture and also facilitate 20 greatly the assembling of the parts in the manufacture of the device. Moreover by having the cast-off strip lie flatly against the back side of the shank and by fastening said cast-off strip to the shank below the end of 25 the downturned portion 2, a construction is provided wherein the head of the tubular rivet or other fastening device does not project beyond the rear face of the bentover portion 2. As a result, the cast-off presents 30 a smooth back face without any projections, for the rear face of the tubular rivet 10 and the rear face of the downturned portion 2 are in substantially the same plane.

The shank 1 of the connector is broadened 35 at its upper and lower ends to such an extent that the length of the bend 2 and the hook 4 is substantially equal to the width of the cast-off strip 8, as shown, forming an effective covering for the back of the connector 40 at all times. Said cast-off strip is of such length that its free end can be turned outward and upward around the hook 4 and against the face of the shank, see Figs. 1 and 5, to close the hook and thereby maintain 45 the suspender-end A in engagement with the hook. The co-operating or socket member 12 of the separable fastening is fixedly attached to the free end of the strip at the outer face thereof in such position that 50 when the strip 8 is turned to hook-closing position the members 11 and 12 of the fastener will co-operate, Fig. 5, and retain the cast-off strip in hook-closing position. At such time the tip 13 of the cast-off strip extends upward above the loop 6 and provides 55 a tab or finger-piece by which the strip can be grasped to separate the fastener 11, 12 when it is desired to open the cast-off and remove the suspender-end A from the 60 hook 4.

From the foregoing description, taken in connection with the drawing, it will be manifest that all pull or strain between the main suspender-web B and the suspender-end A will be transmitted from one to the

other and taken up solely by the metallic connector, independently of the cast-off strip, for the loop 6 is hooked into the throat of the connector and the hook 4 of the latter sustains the suspender-end. Consequently the cast-off strip is never subjected to any strain, and its sole function is to close or open the hook 4, and to provide a finish for the cast-off.

The cast-off is simple in construction, it 75 can be operated readily and quickly, and it is attractive in appearance, while the cost of manufacture is reduced to a minimum.

Various changes or modifications in different details of construction and arrangement may be made by those skilled in the art without departing from the spirit and scope of my invention as set forth in the claims hereunto annexed.

Having fully described my invention, what I claim as new and desire to secure by Letters Patent is:

1. A cast-off for suspenders comprising a metallic hook adapted to detachably engage and sustain the suspender end, said hook 90 having a shank provided at its upper end with a rearward and down-turned portion situated on the opposite side of the shank from the hook and forming with the shank an open cast-off-receiving throat, a cast-off 95 strip overlying the rear face of the shank and having its upper end entered into said throat and covered and protected by said downturned portion, said throat having a width equal to the thickness of said end of 100 the cast-off strip, means for fastening the cast-off strip to the shank below said downturned portion, a loop attached to the terminal portion of the suspender and held in said throat by the upper end of the cast-off strip, the lower free end of the cast-off strip being adapted to be turned upward and outward against the face of the shank to close the hook, and a separable fastener to retain 105 said cast-off strip in hook-closing position.

2. A cast-off for suspenders comprising a metallic hook adapted to detachably engage and sustain the suspender end, said hook having a shank provided at its upper end with a rearward and downturned portion situated on the opposite side of the shank from the hook and forming with the shank an open cast-off-receiving throat, a cast-off 115 strip overlying and situated in engagement with the rear face of said shank, the end of said strip entering said throat and being covered and protected by the downturned portion, fastening means for permanently securing the cast-off strip to the shank, said fastening means being situated below the 120 downturned portion and having the rear face thereof situated in substantially the plane of the rear face of said downturned portion, a loop attached to the terminal portion of the main suspender web and extend- 125 130

ing through said throat and retained there-
in by the end of the cast-off strip, the lower
free end of the cast-off strip being adapted
to be turned outward and upward against
5 the face of the shank to close the hook, and
a separable fastener to retain the cast-off
strip in hook-closing position.

3. In suspenders, a loop carried by the
terminal portion of the main suspender
10 web, a metallic connector having on its up-
per end a loop-receiving hook embracing
said loop and at its lower end a hook to de-
tachably engage and sustain a suspender
end, a cast-off strip overlying the back of
15 the connector and permanently secured

thereto near its upper end, the upper edge
of said cast-off strip engaging the loop and
serving to hold the latter in its hook and the
lower end of said strip adapted to be turned
up around the suspender-end-receiving hook 20
of the connector, and means to detachably
maintain the cast-off strip in hook-closing
position.

In testimony whereof, I have signed my
name to this specification, in the presence of 25
two subscribing witnesses.

ALFRED M. ZIEGLER.
